RAILWAY VEHICLE

Robert N. Janeway, Detroit, Mich., assignor to
Chrysler Corporation, Highland Park, Mich., a
corporation of Delaware

Original application October 1, 1938, Serial No.
232,756. Divided and this application December
11, 1939, Serial No. 308,509

9 Claims. (Cl. 308—184)

My invention relates to railway vehicles and it has particular relation to the construction of railway vehicle trucks.

One object of my invention consists in providing a novel type of railway truck construction which provides improved riding qualities in the car body supported thereby.

Another object of my invention consists in providing a novel type of bearing support for use in a railway truck construction which cushions any forces transmitted between the wheels and the journal bearing supports.

This application is a division of my copending application, Serial No. 232,756 filed October 1, 1938.

For a better understanding of my invention reference may now be had to the accompanying drawing, in which:

Fig. 1 is a side elevational view of a portion of a railway truck embodying certain of the features of my invention.

Fig. 2 is a cross-sectional view of the railway bearing illustrated in Fig. 1, the section being taken along the line II—II thereof.

Fig. 3 is a vertical cross-sectional view of the wheel axle bearing illustrated in Fig. 2, the section being taken along line III—III thereof.

In the structure illustrated the weight of the car body (not shown) is borne by leaf springs 1 which rest on a longitudinally extending lower member 2 of a side frame 3, an upper member 4 of which extends above the springs 1. The end portion of the lower member 2 is inclined upwardly and joins the upper member 4 to constitute the integral side frame structure 3.

The side frames in turn rest, at each end, on journal bearings 5 to be herein later described in detail. The journal bearings 5 receive journals 6, constituting the ends of the axles on which are mounted the usual railway wheels 7.

The side frame 3 may be composed of pressed metal members welded together as shown, the members 14 and 15 constituting opposite sides of the side frame 3 and being welded to a central longitudinally extending web member 16. The members 14 and 15 are each provided with a semi-circular opening 17, within which the journal bearing 5 is secured.

Each of the members 14 and 15 is reinforced by a semi-circular pressed metal member 18 of L-shape cross-section which is welded thereto. The portions 14, 15 and 18 are welded to a semi-circular plate 19, and are provided with integral lugs 20, adapted to receive bolts 21, by means of which a semi-circular retaining member 22 is

adapted to be secured thereto, the members 22 constituting the lower half of a circular enclosure and the members 19 constituting the upper half thereof.

Within the annulus formed by the members 19 and 22 is disposed a plurality of end plates 23 and center plates 24 having annular rubber members 25 vulcanized or otherwise suitably bonded thereto. Each of the end plates 23 has an outer diameter which is greater than the outer diameter of the central plate 24, and the center plate 24 has an inner diameter which is smaller than the inner diameter of the plates 23. The rubber members 25 are vulcanized so as to hold the two end plates 23 and the center plates 24 in a single integral unit of which the metal rings are kept out of contact with each other. The inner periphery of all of the center plates 24 are uniform in diameter and are adapted to fit over and retain an annular bearing housing 28 and the end rings 23 are of uniform external diameter and closely engage the semi-circular members 19 and 22 so as to support the bearing housing on the members 19 and 22 but out of metallic contact therewith.

Within the housing 28 are disposed annular roller races 29 which are adapted to be engaged by a plurality of tapered rollers 30 which likewise engage inner bearing races 31 which are secured to and rotate with the wheel axle 8. The housing 28 is closed, at its outer end, by means of a housing end plate 32 bolted thereto, and is adapted to contain oil or other liquid lubricant so that the rollers on the lower side of the bearing are constantly immersed in oil. The inner bearing race 31 is provided with an oil throwing sleeve 33 which picks up oil at the lowermost point of its travel and throws it outwardly into an opening 34 disposed in the upper part of the stationary housing 28. An oil duct 35 carries the oil by gravity from the opening 34 to the upper part of the bearing so as to constantly bathe those rollers which are, at the moment, in the uppermost position, with oil.

The bearing housing 28 is provided, at one end, with an annular flange 36, as shown in Fig. 2, and at the other end with an annular bolted on flange 37, both flanges being greater in diameter than the inner portions of the support members 19 and 22. Annular plates 38 are secured to the outer sides of the L-section members 18 and in axial alignment with the flanges 36, 37. Disposed intermediate the plates 38 and the flanges 36 and 37 are two annular flexible members 39 each comprising spaced metallic side plates 40

and a central member 41, composed of rubber, which is bonded or otherwise secured to the plates 40. The rubber members 41 prevent any metallic contact between the semi-annular members 18, 19 and 22 on the one hand and the flanges 36 and 37 of the bearing housing on the other hand and at the same time permit a certain degree of flexibility therebetween longitudinally of the wheel axle 6.

Intermediate the flange 36 and the annular flexible member 39 is disposed a ring 50, made in two semi-circular parts and bolted together to form an annulus. This ring, when pulled into place by its bolts, serves to force the flexible member 39 into close fitting engagement with the rings 38 and the flange 37 and cause the flexible members to carry a portion of the vertical load in shear. When the ring 50 is removed, by loosening its bolts, the various parts are no longer held rigidly in place and may be disassembled or adjusted.

The rubber members 25 prevent metallic contact between the axle housing 28 and the semi-circular supporting structures 19 and 22 and at the same time permit a certain amount of resilient movement therebetween in a vertical direction and in a direction longitudinally of the truck frame. These rubber members 25 and 41 therefore act as noise and shock eliminators between the wheels and the side frames and, to the degree that they permit flexibility, serve as load equalizers between the various bearing members. In addition, they provide a cushion between the side members and the wheel axles, thus adding the side frame members to the sprung load leaving only the wheels, axles, wheel bearings and bearing housings to constitute the unsprung load.

In order to eliminate the possibility of incorrectly assembling the bearing housing within the semi-circular members 19 and 22 I have provided the flange 36 with two small spaced lugs 43 at its uppermost point and have welded or otherwise suitably secured a metallic finger 44 to the upper side of the L-shaped member 18, as best shown in Fig. 2, which is adapted to fit between the fingers 43, it being essential that the opening 34 in the housing 28 be at all times assembled in the uppermost position possible so as to provide the proper feeding of oil to the upper bearings.

From this description it will be apparent that there is no metal to metal contact between the wheel axles and the load carrying side frames and that any noises or vibrations transmitted therethrough to the side frames must first pass through layers of rubber adapted for the purpose of eliminating such vibration and deadening such noises.

Although I have illustrated but a single form of my invention, and have described in detail but a single application thereof it will be apparent to those skilled in the art that it is not so limited but that various minor modifications and changes may be effected therein without departing from the spirit of my invention, or from the scope of the appended claims.

I claim:

1. A bearing assembly comprising a shaft, a bearing member surrounding said shaft, a bearing housing enclosing and supporting said bearing member, a supporting member surrounding said housing in radially spaced relation thereto, annular resilient supporting means interposed between said housing and said supporting member comprising a plurality of resilient units each comprising a metallic ring engaging the interior walls

of said supporting member and spaced from said housing, a second metallic ring engaging the exterior wall of said housing and spaced from said supporting member, and a rubber member bonded to both of said metallic rings, resilient means disposed at each end of said supporting member, and means mounted on said housing adapted to engage and hold said last named resilient means in clamping engagement with said supporting member.

10 2. A bearing assembly comprising a shaft, a bearing member surrounding said shaft, a bearing housing enclosing and supporting said bearing member, a supporting member surrounding said housing in radially spaced relation thereto, annular resilient supporting means interposed between said housing and said supporting member comprising a plurality of resilient units each comprising a metallic ring engaging the interior walls of said supporting member and spaced from said housing, a second metallic ring disposed laterally of said first mentioned metallic ring and engaging the exterior wall of said housing and spaced from said supporting member, and a rubber member bonded to both of said metallic rings, resilient means disposed at each end of said supporting member, and means mounted on said housing adapted to engage and hold said last named resilient means in clamping engagement with said supporting member.

15 3. A bearing assembly comprising a shaft, a bearing member surrounding said shaft, a bearing housing enclosing and supporting said bearing member, a supporting member surrounding said housing in radially spaced relation thereto, and resilient supporting means interposed between said housing and said supporting member comprising a plurality of resilient units each comprising two laterally disposed metallic rings, one of said rings having the greater external diameter, and the second ring having the smaller internal diameter, and an annular rubber member bonded to both of said rings, one of said rings being adapted to closely engage the said supporting member and the other being adapted to closely engage the bearing housing, and additional resilient means disposed intermediate the ends of said housing and said supporting member adapted to resiliently oppose relative lateral displacement thereof.

20 4. A bearing assembly comprising a shaft, a bearing means surrounding said shaft, a bearing housing member enclosing and supporting said bearing means, a supporting member surrounding said housing member in radially spaced relation thereto, resilient supporting means including rubber acting in vertical shear interposed between said members, rigid means secured to one of said members in lateral alignment with and spaced from the other member, and resilient means interposed between said rigid means and said other member, said last resilient means including rubber adapted to resist vertical movement between the members in shear and to resist lateral movement between the members in compression.

25 5. A bearing assembly comprising a shaft, a bearing means surrounding said shaft, a bearing housing member enclosing and supporting said bearing means, a supporting member surrounding said housing member in radially spaced relation thereto, resilient supporting means including rubber acting in vertical shear interposed between said members, additional resilient means disposed at the ends of one of said members, and means rigidly secured to the other member adapt-

ed to clampingly hold said additional resilient means in engagement with said first member, said last resilient means including rubber adapted to resist vertical movement between the members in shear and to resist lateral movement between the members in compression.

6. A bearing assembly comprising a shaft, a bearing member surrounding said shaft, a bearing housing enclosing and supporting said bearing member, a supporting member surrounding said housing in radially spaced relation thereto, an annular resilient supporting member disposed intermediate said supporting member and said bearing member, an annular shoulder member mounted on said housing in aligned spaced relation with one end of said supporting member, an annular resilient member disposed intermediate said shoulder member and the adjacent end of said supporting member, a second annular shoulder member mounted on said housing member in aligned spaced relation with the other end of said supporting member, a second annular resilient member disposed in engagement with said other end of said supporting member, and a collapsible clamping member disposed intermediate said second annular shoulder member and said second annular resilient member adapted to move said annular resilient member into clamping engagement with the end of said supporting member.

7. A bearing assembly comprising a shaft, a bearing member surrounding said shaft, a bearing housing enclosing and supporting said bearing member, a supporting member surrounding said housing in radially spaced relation thereto, an annular resilient supporting member disposed intermediate said supporting member and said bearing member, an annular shoulder member mounted on said housing in aligned spaced relation with one end of said supporting member, an annular resilient member disposed intermediate said shoulder member and the adjacent end of said supporting member, a second annular shoulder member mounted on said housing member in aligned spaced relation with the other end of said supporting member, a second annular resilient member disposed in engagement with said other end of said supporting member, and a multi-part ring provided with clamping means for pulling said ring into position between said second shoulder and said second annular resilient member.

8. A bearing assembly comprising a shaft, a bearing member surrounding said shaft, a bear-

ing housing enclosing and supporting said bearing member, a supporting member surrounding said housing in radially spaced relation thereto, an annular resilient supporting member disposed intermediate said supporting member and said bearing member, an annular shoulder member mounted on said housing in aligned spaced relation with one end of said supporting member, an annular resilient member disposed intermediate said shoulder member and the adjacent end of said supporting member, a second annular shoulder member mounted on said housing member in aligned spaced relation with the other end of said supporting member, said shoulder having an inclined inner face, a second annular resilient member disposed in engagement with said other end of said supporting member, and a multi-part ring provided with clamping means for drawing said parts together, said ring parts being mounted on the inclined inner face of said second shoulder and adapted, when drawn together, to move on said inclined shoulder face to clamp together said shoulders, said supporting member, and the intermediately disposed resilient members.

9. A bearing assembly comprising a shaft, a bearing member surrounding said shaft, a bearing housing enclosing and supporting said bearing member, a supporting member surrounding said housing in radially spaced relation thereto, an annular resilient supporting member disposed intermediate said supporting member and said bearing member, an annular shoulder member mounted on said housing in aligned spaced relation with one end of said supporting member, an annular resilient member disposed intermediate said shoulder member and the adjacent end of said supporting member, a second annular shoulder member mounted on said housing member in aligned spaced relation with the other end of said supporting member, said shoulder having an inclined inner face, a second annular resilient member disposed in engagement with said other end of said supporting member, and a multi-part ring provided with clamping ring parts being mounted on the inclined inner face of said second shoulder and adapted when drawn together, to move on said inclined shoulder face to clamp together said shoulders, said supporting member, and the intermediately disposed resilient members, said ring parts being provided with shims and means for receiving said shims to provide the desired degree of compression under said clamping action.

ROBERT N. JANEWAY.
